BLADE STROPPING DEVICE

Frank J. Schalow, Brooklyn, N. Y.

Application September 29, 1939, Serial No. 297,092

9 Claims. (Cl. 51—221)

This invention relates to devices for use in the stropping of blades and particularly single and double edged safety razor blades. More particularly the invention consists in the provision of an elongated rectangular hone having a treated upper surface and a blade holding member generally yoke-shaped in form to straddle the hone and extend over the treated surface thereof so as to provide manual or other movement of the blade holder longitudinally of the hone and over said treated surface; a further object being to provide a blade holder consisting of hingedly coupled parts within and between which a razor blade is adapted to be keyed and supported with means for arranging said part or the blade therein at an inclination to the surface of a hone to dispose the beveled edge of the razor blade in proper relationship to said surface in the sharpening of the blade; a still further object being to provide a holder so constructed as to support the edge of a blade in an angular position transversely of the hone other than at right angles thereto; and with these and other objects in view the invention consists in a device of the class and for the purpose specified, which is simple and economical in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a plan view of one form of device which I employ with part of the construction broken away.

Fig. 2 is a partial section on the line 2—2 of Fig. 1.

Fig. 3 is a section on the line 3—3 of Fig. 1.

Fig. 4 is a view similar to Fig. 1 but showing only a part of the construction.

Fig. 5 is a section on the line 5—5 of Fig. 4, and

Fig. 6 is a view similar to Fig. 2 showing a modification.

In carrying my invention into effect, I preferably provide an elongated rectangular hone body 10 in the form of a strip of plate glass, upper corner portions of which or edges of which are beveled as seen at 11 in Fig. 1 of the drawing. The upper surface 12 of this glass is specially treated to provide thereon a desirable hone surface. The surface is prepared by using a suitable abrasive in substantially powdered form together with water or other fluid agent

to form a paste-like substance thereof and in arranging said substance between two strips of glass and in rubbing or agitating these strips one with respect to the other to produce what might be termed a finely ground surface 12.

I also find that this same result can be accomplished by using a suitable disc or pad which is rubbed or reciprocated over the surface 12 with the grinding or other compound thereon. In this connection it is to be noted that ground glass of more or less conventional construction, or in other words produced in accordance with known methods, for the heretofore known uses of ground glass are not satisfactory to produce the advantageous results which I have accomplished in the use of a glass hone prepared in the manner defined. In other words, it is desirable to produce a surface 12 which has what might be termed a soft or velvety texture in the passage of the finger of the hand thereover rather than a coarse or rough texture, thereby producing a very fine stropping action upon the blade avoiding any tendency to scratch or mar the cutting edge of the blade as will be apparent.

In Figs. 1 to 3 inclusive I have shown one form of blade holder 13 consisting of a base plate 14 having depending side walls 15 forming a channel-shaped block of the plate for slidable engagement with the strip 10, the side walls or flanges 15 fitting loosely over the side edges 10a of the strip 10 to guide the blade holder in its movement longitudinally of said strip. The rear end of the plate 14 has downwardly extending supporting feet 16 at the corner portions thereof which are adapted to rest upon the upper surface 12 of the hone strip 10 and to support the plate 14 in an inclined position. The other forward edge of the plate 14 is cut away as seen at 17 so that the side walls 15 project therefrom as seen at 15a to form pivots for a blade retaining plate 18 also having side walls 18a arranged over the walls 15, the walls 18a being pivoted to the extensions 15a as seen at 19.

The plate 14 has two transversely spaced outwardly protruding pins 20 which are adapted to enter corresponding apertures 21 in a double edged razor blade 22 in keying the blade against movement on the plate 14. The retaining plate 18 is also provided with apertures 23 for receiving the pins 20, thus retaining the blade 22 against displacement from the holder. The beveled edges of the blade 22 are indicated at 22a and 22b, and by supporting the plate 14 in the inclined position as is clearly illustrated in Fig. 2,

the beveled edges 22a, 22b of the blade may be supported in the proper position upon the surface 12 in the sliding movement of the holder longitudinally of the strip 10 in stropping or sharpening these edges, it being understood that the blade 22 must be turned in sharpening all four beveled sides of the two edges 22a, 22b. This is done very simply by raising the plate 18 on the pivot 19.

It will of course be understood that the forward end portion 18b of the retaining plate 18 extends beyond the cut-away or recessed edge of the plate 14 and is disposed over the edge of the blade 22, it being sharpened so that by applying light pressure to the device 13 while holding it between the fingers of a hand, the beveled surface of the blade edge arranged upon the surface 12 will be stropped or sharpened most effectively. It requires but a few strokes of the device over the surface 12 to accomplish this result unless the razor blade is in very poor condition. In this connection, however, it will be understood that it is not the intention to provide a device for regrinding a razor blade, but rather a device which will function in the manner of a strop to simply renew the edge of a blade which has become somewhat dull, or in other words, has lost its fine easy cutting edge. By the use of a device of this type and kind, the life of a razor blade may be more or less indefinitely maintained.

The honing strip 10 is made of sufficient width as is also the holder to support the side edges of the blade well within the side boundaries of the hone as is clearly illustrated in Fig. 1 as well as in the modified showing in Fig. 4.

In Fig. 6 of the drawing I have shown a slight modification of the structure shown in Fig. 1 which simply consists in providing a plate 24 substituted for the plate 14 and differentiating therefrom in omitting the pins and providing instead a long socket 25 to receive part of the enlarged crosshead 26 of a single edge razor blade 27. With this construction the plate 28 is substituted for the plate 18 and is provided with a socket portion 29 for receiving the other part of the crosshead 26 to key the blade 27 against displacement. The supporting feet 30, similar to the feet 16, are provided to maintain the angular position of the plate 24, and the two plates 24, 28 are pivoted together as indicated at 31 in the same manner as the pivot at 19. The device as shown in Fig. 6 is otherwise the same and is operated in the same manner as the device shown in Figs. 1 to 3 inclusive, it being understood, however, that the blade 27 need be turned only twice in sharpening the same, rather than turned four times as in sharpening the double edge blade. At this time it will also be apparent that the structure or mounting of a single edge blade as shown in Fig. 6 is applicable to the angular blade mounting as is taught in Figs. 4 and 5 of the drawing.

In the latter figures, 32 represents a plate similar to the plates 14, 24, but instead of having the feet 16 and 39, an anti-frictional roller 33 is employed to support the plate 32 in the inclined position desired, the roller being mounted on a transverse pin 34 which is secured in the side walls or flanges 35 of the plate. The recessed portion 36 of the plate will have downwardly extending bearings 37 for reinforcing the mounting of the roller 33 as will be apparent. At 38 is shown a plate substituted for the plates 18 and 28 and is pivoted to the side walls or flanges 35 as seen at 39, the plate 38 having similar walls

or flanges 38a. The forward edge 40 of the plate 32 as well as the forward edge 41 of the plate 38 are angularly disposed in the sense that they are not arranged at right angles to the longitudinal plane of the device as in the structure shown in Figs. 1 to 3 inclusive so as to dispose the edge or edges of the razor blade in a corresponding angular position which will in some instances, produce a more desirable sharpening or stropping action. With this construction, the key pins 42 on the plate 32 which are similar to the pins 20 will also have the same angular relationship, as will the apertures 43 in the plate 38 for receiving said pins.

At this time it will be apparent that any suitable keying means may be provided between the hingedly coupled plates of my holder to suit different types and kinds of blades to be stropped or sharpened. The important feature is to provide a holder for a blade or tool of the character described, which will support the edge which is to be sharpened in the proper angular relationship with respect to the surface of the hone employed as a sharpening medium, as well as in the angular position as illustrated in Figs. 4 and 5 so that the blade edge being sharpened is disposed at an angle other than 90° to the path of movement of the holder over the hone surface.

It will be apparent that in view of the simplicity in the construction of the device as a whole, the same may be sold at a very reasonable retail price and at the same time a very simple, neat and practical blade sharpener is provided. The device may be made from metal or from other non-metallic material, suitable for the purpose.

Having fully described my invention, what I claim as new and desire to secure by Letters Patent, is:

1. A blade sharpening device of the class described comprising in combination with an elongated hone having an upper sharpening surface, of a yoke-shaped blade supporting member straddling said hone and guided in the movement of said member longitudinally of the hone by the yoke-shaped contour thereof, said member comprising movably coupled plates, means for keying and supporting a blade between adjacent surfaces of said plates to support the cutting edge of the blade in direct contact with the upper surface of said hone, and means for supporting said member and the blade therein in an upwardly inclined position with respect to said surface in maintaining the desired contact of the cutting edge of the blade with said surface.

2. A blade sharpening device of the class described comprising in combination with an elongated hone having an upper sharpening surface, of a yoke-shaped blade supporting member straddling said hone and guided in the movement of said member longitudinally of the hone by the yoke-shaped contour thereof, said member comprising movably coupled plates, means for keying and supporting a blade between adjacent surfaces of said plates to support the cutting edge of the blade in direct contact with the upper surface of said hone, means for supporting said member and the blade therein in an upwardly inclined portion with respect to said surface in maintaining the desired contact of the cutting edge of the blade with said surface, said last named means comprising an anti-frictional member.

3. A razor blade sharpening device of the character described adapted for use with a hone of predetermined width, said device comprising a blade holder composed of two pivotally coupled parts, one of the parts being yoke-shaped in cross sectional form to provide a wide top plate having depending side walls adapted to engage the side walls of said hone, the other part having a plate disposed over the top plate of the first named part with the forward edge thereof projecting beyond the corresponding edge of the top plate of the first part, means keying and supporting a razor blade between adjacent surfaces of the plates of said parts in a manner to dispose the edge thereof to be sharpened in alignment with the forward edge of said second part, and means supporting said holder in angular position with respect to said honing surface in sharpening a blade supported therein.

4. A razor blade sharpening device of the character described for use with an elongated honing member, said device comprising upper and lower interfitting parts of yolk-shaped cross sectional form, each part having a wide blade engaging plate with flanges at opposite sides thereof protruding forwardly of the front edge portion of said plate, means pivotally coupling said flanges at the extremity of said protruding portions, the forward edge portion of the upper plate protruding beyond the forward edge of said lower plate sufficiently to overlie and shield the edge of a blade engaged between said plates, the protruding portion of said flanges being adapted to extend along side edges of said honing member, and means at the rear edge portion of said lower plate for supporting said device in a predetermined inclined position with respect to said honing member.

5. A razor blade sharpening device of the character described for use with an elongated honing member, said device comprising upper and lower interfitting parts of yolk-shaped cross sectional form, each part having a wide blade engaging plate with flanges at opposite sides thereof protruding forwardly of the front edge portion of said plate, means pivotally coupling said flanges at the extremity of said protruding portions, the forward edge portion of the upper plate protruding beyond the forward edge of said lower plate sufficiently to overlie and shield the edge of a blade engaged between said plates, the protruding portion of said flanges being adapted to extend along side edges of said honing member, means at the rear edge portion of said lower plate for supporting said device in a predetermined inclined position with respect to said honing member, the axis of the pivot coupling between said parts being substantially at right angles to the direction of movement of said device on the honing member and the front edge of said plates being arranged at an angle to said axis.

6. A device for holding a blade in the operation of sharpening the same, said device comprising plate-like members having interfitting side flanges pivotally coupled at one end of said device, the member forming the lower part of said device having the forward edge thereof adjacent the pivots of said flanges disposed inwardly of the corresponding edge of the upper member, means at the opposed edge of said lower member for supporting the same in raised position, means on said members adapted to engage and support a blade therebetween, and said last named means being arranged to dispose the edge of the blade in alignment with the forward edge of said upper member.

7. A device for holding a blade in the operation of sharpening the same, said device comprising plate-like members having interfitting side flanges pivotally coupled at one end of said device, the member forming the lower part of said device having the forward edge thereof adjacent the pivots of said flanges disposed inwardly of the corresponding edge of the upper member, means at the opposed edge of said lower member for supporting the same in raised position, means on said members adapted to engage and support a blade therebetween, said last named means being arranged to dispose the edge of the blade in alignment with the forward edge of said upper member, and the forward edges of said members as well as the blade engaging means thereof being arranged angularly to the side flanges of said members, whereby longitudinal movement of said device with a blade supported therein will operate to move the blade diagonally with respect to a honing surface.

8. A device for holding a razor blade in the operation of sharpening the same, said device comprising a pair of members pivotally coupled at the forward ends thereof, means for keying a blade between said members to dispose the edge of the blade in alignment with the forward edge of said device, and means at the opposite edge of the device for supporting the same in inclined position.

9. A device for holding a razor blade in the operation of sharpening the same, said device comprising a pair of members pivotally coupled at the forward ends thereof, means for keying a blade between said members to dispose the edge of the blade in alignment with the forward edge of said device, means at the opposite edge of the device for supporting the same in inclined position, said last named means being integral with the lower member of said device, and the forward edge of said lower member being arranged inwardly of the forward edge of the upper member sufficiently to expose the lower surface of the blade edge to a honing surface.

FRANK J. SCHALOW.
